CLAIM

The ornamental design for beverageware, as shown and described.

DESCRIPTION

FIG. 1 is a perspective view of a first embodiment of beverageware showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is top plan view thereof;

FIG. 7 is bottom plan view thereof;

FIG. 8 is a perspective view of a second embodiment of beverageware that includes a lid having a transparent or translucent surface. The remaining elevational and plan views correspond to FIGS. 2-7, except that the lid of the second embodiment has a transparent or translucent surface;

FIG. 9 is a perspective view of a third embodiment of beverageware showing my new design;

FIG. 10 is a left side elevational view thereof;

FIG. 11 is a right side elevational view thereof;

FIG. 12 is a front elevational view thereof;

FIG. 13 is a rear elevational view thereof;

FIG. 14 is top plan view thereof;

FIG. 15 is bottom plan view thereof; and,

FIG. 16 is a perspective view of a fourth embodiment of beverageware that includes a lid having a transparent or translucent surface. The remaining elevational and plan views correspond to FIGS. 10-15, except that the lid of the fourth embodiment has a transparent or translucent surface. The broken lines illustrate unclaimed portions of the beverageware that form no part of the claimed design. The oblique shade lines of FIGS. 9 and 15 indicate a transparent or translucent surface.
